ATTORNEY.

UNITED STATES PATENT OFFICE

CHARLES J. THOMAS, OF LANSDOWNE, PENNSYLVANIA, ASSIGNOR TO KIWI MFG. CO.,
INC., OF PHILADELPHIA, PENNSYLVANIA, A CORPORATION OF DELAWARE

CUSHION SPRING

Application filed May 28, 1930. Serial No. 456,366.

This invention relates to cushion springs and more particularly to springs used in mat assemblies to form an inner cushion member in mattresses, pillows, and similar cushion elements.

There has been a great deal of activity in this art heretofore looking to the provision of springs and spring assemblies which would furnish the greatest spring efficiency

10 with the lowest possible assembling costs. In most cases the mat or spring assemblies have been provided as a series of juxtaposed individual springs with mechanical fastening devices engaging adjacent portions of the springs to place them under lateral restraint relative to each other. In some cases such mat assemblies have been housed in woven fabric containers. As delivered to the user heretofore, these mat assemblies have 15 been of certain standard predetermined sizes and forms which in certain instances have not coincided with the sizes of mattresses or cushions desired to be made by the mattress manufacturer, and he has been concerned 20 with the necessity of attempting either to add additional spring units to the preformed assembly or to remove certain of the units from the assembly provided. With the facilities available to him this has been difficult.

25 Moreover, the fabric containers although adding appreciably to the cost of the spring mat assemblies, have been considered helpful heretofore in reducing metallic noises incident to the relative movement between adjacent spring elements. There have also in the past been some attempts to produce spring units each of which was deformed to form one or more complementary locking or interlocking devices so as to eliminate independent

30 mechanical ties or fastening devices and to permit direct locking of the springs together. These attempts in the past have been relatively unsuccessful owing to certain factors which are briefly summarized as follows: In 35 the great majority of such devices it has been attempted to deform the spring so that there will be on one half of the spring a male locking element, and the other half a female locking element, with a consequent necessity 40 of exactly proper disposition of the spring

elements in order to bring the proper cooperating locking portions into juxtaposition, which interferes materially with the speed and ease of assembly and to such a degree as to militate against the use of the devices; in 55 most of these devices it was necessary to use tools to insure proper interlocking connection between the complementary portions of the spring elements, such tools as pliers, tweezers, and the like; certain of the prior art devices 60 only locked adjacent springs against tensile strains and were liable to come open when a pair of adjacent springs were subjected to lateral compression; in some of the illustrations 65 of prior art the respective upper and lower surfaces of the spring mat assembly were not smooth, so as to facilitate the imposition of the filling material but, on the contrary were possessed of protuberances which were undesirable; and, of great importance, the previous 70 attempts in the field have evolved spring mat assemblies which were noisy and hence undesirable owing to the presence of a greater or less amount of play in the interlocking 75 connections.

75 It is among the objects of this invention; to obviate the disadvantages of prior constructions; to provide spring units of resilient material having integral locking lugs 80 mutually engageable by a flexing manipulation of a spring; to provide a spring mat assembly, in which integral portions of the springs form interlocking connections with adjacent springs, which is simple, economical 85 and quiet; to provide a spring unit with a plurality of substantially identical integral locking elements; to provide an improved form of interlocking connection between spring elements which is substantially free 90 from play; to provide a plurality of spring elements which can be easily and quickly interlocked by hand without the use of pliers or similar tools; to provide a spring assembly formed of a plurality of relatively interlocked springs the upper and lower surfaces 95 of which are substantially free of protuberances; to provide a plurality of springs having integral locking lugs arranged for interlocking engagement by manipulations of the 100 springs different from any flexing that

might arise from normal use of the assembled springs; in addition to other objects and advantages as will become more apparent as the description proceeds.

6 In the accompanying drawing;

Fig. 1 represents a perspective of four springs in assembled relation according to this invention with one of the springs broken away to prevent confusion,

10 Fig. 2 represents a perspective of the manner of locking a pair of springs according to this invention with the springs partially broken away, and

15 Fig. 3 represents a fragmentary perspective of the interlocking unit formed by the complementary portions of a pair of adjacent springs.

According to the present invention the springs, as 10 and 11, may be of the hour 20 glass or any other type and terminate at the top and bottom, respectively, in upper turns 12 and 13 and lower turns 14 and 15, one or more of the lower turns may be treated and act the same as an upper or end turn, as will 25 be obvious. The respective upper and lower turns may be in a substantial plane as is common and the free ends of the springs may be locked, or open as disclosed for illustrative purposes in Fig. 1. At a suitable distance 30 from the free end 16 of a spring there are formed integral, resilient, substantially closed, generally radially extending, triangular lugs 17. As the lugs on all of the springs, and on all sides of the springs, are substantially 35 identical, but one will be described in detail. The upper turn 12 is bent outwardly in an acute angle as at 18 in the formation of a leg 20 of the triangular locking lug. Leg 20, although starting out in the common 40 plane of the turn 12, is bent downwardly in its juncture with the integral base 21 into which it merges and which extends arcuately parallel to turn 12, but in a plane preferably lower than that of the end turn 12. 45 The base 21 of the triangular locking lug merges, in an acute angle, into the leg 22, which, in turn, inclines upwardly to form an acute angle 23, merging again into the end turn 12. It is to be noted that the knuckles 50 formed by the junction or emergence of legs 20 and 22 with the turn 12 are substantially and preferably in contact. There may be a gap 55 between the knuckles, the desirable thing (although it is not essential) being that the gap, if any, between these knuckles be small enough to prevent the passage of a wire of the thickness of the turn of wire, forming the spring, without flexing the wire of the triangular locking lug. It will be understood 60 that after flexing the turn 12 to open or widen the gap between knuckles 18 and 23 release of the turn 12 will permit the parts to spring together owing to the inherent resilience of the wire. It also will be understood 65 that the opposite cooperating triangu-

lar locking lug on end turn 13, is formed in substantially the same manner as has just been described for locking lug 17 on end turn 12.

With the individual springs formed with 70 a plurality, preferably four, of diametrically oppositely formed triangular locking lugs, it will be understood that the springs may be arranged and seized by the operator in any order in which they may fall in the 75 formation of a spring mat, as it makes no difference which locking lug is locked first or last and there are no distinctions as to male or female locking elements. The operator, 80 in order to assemble a given pair of springs, (and the same operation continued indefinitely completes a mat of a desired area) takes a spring in each hand, 85 brings them toward each other with the upper turn 12 of one spring at substantially 90° to the upper turn 13 of an adjacent spring so that the closed end formed by the substantially abutting knuckles 18 and 23 of locking lug 17 on one spring, are in alignment or 95 actual contact with a leg 20 of the opposite complementary locking lug. This brings the parts to the position shown in Fig. 2. The spring wire, being resilient, may flex about the junction of legs 20 and 22 with the base 99 100 105 110 115 120 125 130 135 140 145 150 155 160 165 170 175 180 185 190 195 200 205 210 215 220 225 repeat the process of twisting one wire to substantially 90° of the other then flexing open the desired lug when the interlocking association can be broken.

5 It will be understood that each of the lugs is attached to its cooperating juxtaposed lug in the same manner, which is well within the resilient range of the springs as formed.

It will be noted that the springs as thus assembled require no tool manipulations, and yet are so firmly interlocked as absolutely to prevent undesired unlocking operation in any normal use of the springs, and yet, that owing to the peculiar locking assembly, the 10 freedom of operation of the mat assembly is maintained. It will be obvious that the locking lugs according to this invention may be applied to other turns of the spring than the end turns, and if desired the locking legs 15 instead of all being bent from the plane of the terminal or other turn, in the same direction, may be turned in different directions and such modifications are to be construed as within the scope of this invention unless otherwise limited by the appended claim.

I claim:

In a spring mat assembly, a plurality of springs each having an end turn in a common substantial plane, at least four identical locking lugs formed on each end turn in accurately spaced relation, each lug comprising a radially extending projection having a pair of inwardly converging legs and each lug inclined out of the substantial plane of the end turn and also out of a plane perpendicular of the plane of the end turn to the same identical degree of inclination, and so arranged that any selected lug of one spring may have interlocking engagement with any selected lug of an adjacent spring in the assembly, that said interlocking engagement may be had by selectively engaging either lug within the other, said lugs so arranged as to permit interlocked relation while maintaining the respective end turns in the common substantial plane.

Signed at Philadelphia, county of Philadelphia, and State of Pennsylvania, this 27th day of May, 1930.

CHARLES J. THOMAS.
